UNITED STATES PATENT OFFICE.

WILLIAM B. HEWITT, OF HOLYOKE, MASSACHUSETTS, ASSIGNOR, BY MESNE ASSIGNMENTS, TO WORTHINGTON PUMP AND MACHINERY CORPORATION, OF NEW YORK, N. Y., A CORPORATION OF VIRGINIA.

PUMP.

1,331,504.

Specification of Letters Patent.

Patented Feb. 24, 1920.

Application filed October 30, 1915. Serial No. 58,776.

To all whom it may concern:

Be it known that I, WILLIAM B. HEWITT, a citizen of the United States, residing at Holyoke, county of Hampden, and State of Massachusetts, have invented certain new and useful Improvements in Pumps, fully described and represented in the following specification and the accompanying drawings forming a part of the same.

10 This invention relates to that class of pumps used especially for the transportation of oil through pipe lines. In this service, because of the necessity for continuous operation, the penetrating nature of the material handled, and the fact that pumping plants are located in many cases at a great distance from the base of supply and repair, these pumps must be extremely rugged, simple in construction and with their parts 20 readily accessible.

The especial object of this invention is the production of a pump of this class which shall meet these requirements with approximately straight direct flow of the oil through 25 the pump, small clearances and, large valve area, whereby higher plunger velocities may be obtained and tortuous passages and large clearance spaces be avoided. For use with a pump of this kind a special valve construction has been developed in which the valve parts are readily accessible and easily 30 removable, and this forms in itself a specific feature of the invention.

In the accompanying drawings forming a 35 part of this specification an oil line pump embodying all the features of the invention in their preferred form is shown, and this construction will now be described in detail and the features forming the invention then 40 specifically pointed out in the claims.

In the drawings—

Figure 1 is a side elevation, partly in section, to show the cylinder and valve construction;

45 Fig. 2 is a plan view showing a two pump construction.

Fig. 3 is a section on the line 3—3 of Fig. 1, showing the valve construction in detail;

50 Fig. 4 is a similar view showing a modified valve construction.

Referring to the drawings, A is the pump head frame carrying crank-shaft B shown

as driven by gear C from power shaft D and gear E. Cranks 10 are mounted on crank-shaft B having pitmen 11 connected to cross-heads 12, which in turn are connected to the pump plungers 13 by the yokes 14 and rods 15. Suitable cradles 16 with cross-head guides are provided. The pump cylinder is made up of two pump cylinder sections 18 60 having their force chambers 24 integral with the cylinders, the cylinders being bolted together at their force chamber ends, and provided with flanges 19 for connection to the cradles 16, the usual outside packed plunger glands 20 being shown. Cylinder sections 18 with their individual valve chambers are cast integral and the cylinders are interchangeable. A common suction breeches 21 forms the suction chamber for the inlets 22 70 of the two cylinder sections and connects with the suction pipe line 23. The suction valves 29 preferably open into the cylinder beyond the plunger stroke, thus reducing the clearance. The force chamber 24 has 70 discharge ports 25 for the pump cylinders controlled by discharge valves 30, and discharge openings 26 connected by common discharge pipe 27 to the discharge pipe line 28. The discharge ports 25 are slightly 80 larger than the suction ports 22, and are in alignment therewith. Suitable hand holes and covers are provided above the discharge valves to provide a ready access to the valves.

Fig. 3 shows a valve construction well adapted for use in a pump of this kind, in which 22 and 25 are, respectively, the suction and discharge ports having valve seats 1 and 2 mounted therein. Through the 90 valve seats passes a heavy rod or bolt 3 which also passes through the bottom of the suction chamber 21 and is secured by cap nut 4. Below the valve seat 1 the bolt 3 carries collar 6. Suction valve 29 moves upon a hollow valve stem 7 provided with a head 8 screw threaded on the threaded portion 5 of the bolt 3. A spring 9 between the valve and the head 8 presses the valve upon its seat. The discharge valve construction is 100 identical with that of the suction valve, except that the valve stem for the discharge valve is provided with a loop 10 above the nut portion to enable the entire valve con-

struction to be withdrawn from the pump cylinder upon the release of cap nut 4.

Fig. 4 shows a variation of the valve construction shown in Fig. 3, in which 1 and 2 are respectively the suction and discharge valve seats. Upon the valve seats 1 and 2 are seated, respectively, suction and discharge valves formed of ball valves 31, 32, and caps 34, 35. A rod or bolt 36 screw 10 threaded on each end is screwed into the top of the valve cap 34 and passes through the valve seat 2 and cap 35, and is capped by a cap nut 37. Into the bottom of the valve cap 34 is screwed a rod or bolt 38 carrying 15 a collar 6. A collar nut 39 passes through stuffing box 40 in the bottom of the suction chamber 21 and engages the screw threaded end of the bolt 38.

It will be seen that the valve mounting 20 provides for the convenient removal of the discharge valve and its seat independently of the suction valve and its seat, that both the valves and their seats may be removed successively without removing the rod on 25 which the parts are mounted, and that by removing the cap nut 4 of Fig. 3 or unscrewing the nut 39 from rod 38 of Fig. 4, the entire valve and valve seat construction may be removed as a unit with the rod. In the 30 preferred construction shown in Fig. 4, also, it will be seen that rod 38 may be released without removing the nut 39 and its packing 40, so that the suction chamber 21 is not opened by the removal of the rod. The 35 tire valve and valve seat construction can thus be removed without draining the suction chamber.

The pump construction is very simple to manufacture, requires a minimum of care in 40 foundry work, assures a leak-proof casting by the integral valve chambers and the cylinder sections are readily interchangeable. The distance from the floor to the underside of the discharge valve is minimized thereby 45 materially reducing the total suction lift from that used in the ordinary type of pot valve where the discharge valves are located high above the oil cylinder. The simplicity of the cylinder section casting is increased 50 by the separate valve seats, eliminating the likelihood of breakage and increasing the accessibility of all the valve parts for removal.

What I claim is:

55 1. A double acting center discharge pump having a cylinder formed of two cylinder sections, each cylinder section formed in a single casting with its valve chamber in line with the plunger and beyond the plunger 60 movement, and suction and discharge ports in the valve chamber ends of the cylinder sections.

65 2. A double acting center discharge pump having a cylinder formed of two cylinder sections, each cylinder section formed in a

single casting with its valve chamber in line with the plunger and beyond the plunger movement and the sections being bolted together at their valve chamber ends, and a single suction chamber for both sections. 70

3. A pump having a cylinder formed of two cylinder sections, each cylinder section and its discharge chambers formed in a single casting and bolted together at their discharge chamber ends, suction and discharge 75 ports in the discharge chamber ends of the cylinder sections and beyond the plunger movement, and suction valves mounted to open inside the cylinder sections opposite the discharge ports and beyond the plunger 80 movement.

4. A pump having a cylinder formed of two cylinder sections, each cylinder section and its discharge chamber formed in a single casting and bolted together at their discharge chamber ends, suction and discharge 85 ports in the discharge chamber ends of the cylinder sections and beyond the plunger movement, suction valves mounted to open inside the cylinder sections opposite the 90 discharge ports and beyond the plunger movement, and suction and discharge valve seats and valves connected together to be inserted and removed as a unit. 95

5. A pump cylinder having a valve chamber integral therewith, suction and discharge valve seats formed separately from the cylinder and arranged in line with each other, suction and discharge valves, a valve rod on which the suction and discharge 100 valves and valve seats are mounted, devices secured on the rod for holding the rod in place and engaging the valves and valve seats thereon, arranged for the removal of one valve and its seat from the rod while retaining the other valve and its seat in place or removing both valves and their seats from the rod successively, and removable holding devices for the rod whereby the rod with the valve and valve seats thereon may 110 be withdrawn from the valve chamber. 105

6. A pump cylinder having a valve chamber integral therewith, suction and discharge valve seats formed separately from the cylinder and arranged vertically in line 115 with each other with the suction valve seat below, suction and discharge valves, a valve rod on which the suction and discharge valves and valve seats are mounted, devices for holding the rod in place and engaging the valves and valve seats thereon arranged for the removal of the discharge valve and its seat from the rod while retaining the suction valve and its seat in place or removing both valves and their seats from the rod 125 successively, and holding devices for securing the lower end of the rod in the suction chamber wall, including a packing device arranged to release the rod without permitting escape of fluid, whereby the rod with 130

the valves and valve seats thereon may be withdrawn from the valve chamber without draining the suction chamber.

7. A valve chamber having suction and discharge valve seats set therein in line with each other, a rod on which the valve seats are mounted, suction and discharge valves mounted on the rod, independently removable holding devices secured on the rod for the discharge valve and for the suction valve whereby one of the valves and its seat may be removed from the rod independently of the other or both valves may be removed successively, and removable holding devices for securing the rod in place whereby the rod may be removed with both the valves and their seats thereon.
8. A valve chamber having suction and discharge valve seats set therein in line with each other, a rod on which the valve seats are mounted, suction and discharge valves mounted on the rod, independently removable holding devices on the rod for the discharge valve and for the suction valve whereby the discharge valve and its seat may be removed upward from the rod independently of the suction valve and its seat or both valves and their seats may be removed suc-

cessively, and removable holding devices for securing the rod in place in the suction chamber wall including a packing device arranged to release the rod without permitting escape of fluid from the suction chamber, whereby the rod may be moved with both valves and their seats thereon without draining the suction chamber.

9. A valve chamber having suction and discharge valve seats and valves therein in line with each other, a rod on which the valves and valve seats are mounted, holding devices for the valves on the rod, and holding devices for securing the rod in place in the suction chamber wall including a packing device arranged to release the rod without permitting escape of fluid from the suction chamber, whereby the rod may be removed with both valves and their seats thereon without draining the suction chamber.

In testimony whereof, I have hereunto set my hand in the presence of two subscribing witnesses.

WILLIAM B. HEWITT.
